UNITED STATES PATENT OFFICE.

LOUIS WIMMER, OF ELIZABETHPORT, NEW JERSEY, ASSIGNOR OF ONE-THIRD TO SAMUEL LEVENS, OF ELIZABETH, NEW JERSEY, AND ONE-THIRD TO ABRAHAM MARX, OF NEW-ARK, NEW JERSEY.

LEATHER-BLACKING MACHINE.

No. 883,438.

Specification of Letters Patent. Patented March 31, 1908.

Application filed May 25, 1907. Serial No. 375,613.

To all whom it may concern:

Be it known that I, LOUIS WIMMER, a citizen of the United States, residing at Elizabethport, in the county of Union and State of New Jersey, have invented certain new and useful Improvements in Leather-Black-
ing Machines, of which the following is a specification.

The objects of the invention are to enable
10 the blacking of leather to be effectually ac-
complished with great facility; to obtain a
highly finished product of great permanency
or durability, and to save time, labor and ex-
pense in producing it; to this end to provide
15 a machine in which different sets of brushes
for applying different dressings are arranged
contiguous to a cylinder over which the
leather passes; to thus secure closely suc-
cessive applications of the different dressings;
20 to provide suitably tangential feed and dis-
charge boards for said cylinder, and to ob-
tain other advantages and results as may be
brought out in the following description.

Aside from blackening leather, the inven-
25 tion may be employed for coloring, staining,
gumming, pasting, seasoning or finishing
leather by the application of any known
dressings, and although I have for purpose of
illustration shown a blacking machine, and
30 so refer to the invention herein, I do not wish
to be understood as limiting myself thereby
except as the state of the art may require.

Referring to the accompanying drawings,
35 in which like numerals of reference indicate
corresponding parts in each of the several
figures, Figure 1 is a side elevation of a ma-
chine of my improved construction, through
viewed in the drawings; Fig. 2 is a plan of
40 the same; Fig. 3 is a vertical longitudinal
section taken on line x, Fig. 2, looking in the
direction indicated by the arrow, and Fig. 4
is an elevation of the machine from the side
opposite that shown in Fig. 1.

45 In said drawings, 1 indicates a bed plate,
with side frames 2, 3 of any suitable con-
struction adapted to support the working
parts of my machine mounted thereon. A
driving shaft 4 journaled in said side frames
50 2, 3, projects at one side of the machine to
receive fast and loose pulleys 6 and 7, and
carries between the side frames a cylinder 8
keyed to the said shaft 4. Also upon the
other end of this shaft 4 outside the side
55 frame 3, a large gear 9 is mounted to rotate

loose upon the shaft, being held against
slipping off by a collar 10. The said gear 9
is driven by a smaller gear 11 mounted on a
shaft 12 transversely journaled in the side
frames 2, 3, and adapted to be driven by fast 60
and loose pulleys 13, 14.

At the rear of the machine, or left-hand
end as shown in Figs. 1, 2 and 3, is a feed
board 15, and at the front or opposite end of
the machine is a discharge board 16. Each 65

of these boards is arranged between the side
frames 2, 3 of the machine, and is mounted
thereupon, as by brackets 17, (or 18), and
cross-braces 19, (or 20), extending trans-
versely from one side frame to the other; 70
furthermore, each board inclines or slants
downwardly away from the cylinder 8, to
which its upper edge is adjacent. Said
feed and discharge boards are thus tangent
to the upper part of the cylinder, and form 75

with said upper part a ridge or rounded edge
over which the leather is adapted to pass, it
being remembered that the cylinder rotates
in the direction shown by the arrow. Ad-
jacent to the upper part of this ridge, or in 80
other words, to the surface of the cylinder 8,
between the feed and discharge boards, are
arranged a plurality of sets of brushes for
applying the desired dressings or blacking to
the leather, said brushes and their asso- 85

ciated parts extending longitudinally of the
cylinder and being mounted in or upon the
side frames 2, 3 of the machine. In the
blacking machine shown, the first of these
sets of brushes, or one nearest the rear of the 90

machine, is for applying the sig or first coat-
ing to the leather, and comprises a supply
pan 21, a supplying roller 22 dipping at its
lower part into said pan, an applying brush
23 in suitable contact with said supply roller 95
22 to receive sig therefrom and adapted to
also engage a piece of leather passing over
the cylinder 8 to apply said sig thereto, and a
rubbing-in brush 24, adapted to subsequently
engage the leather to thoroughly work said 100
sig into the pores of the leather. The second
or foremost set of brushes is for applying the
finishing coat of black, varnish or other
dressing to the leather, and comprises a
supply pan 25, supplying roller 26, applying 105
brush 27, and rubbing-in brush 28, all said
parts being similar to, and arranged in the
same relation as, the corresponding parts
described in detail in connection with the
first set.

Preferably, the surfaces of the supply rollers 22 and 26 are provided with pockets or recesses 29 drilled therein, to facilitate their furnishing an ample quantity of dressing to the respective brushes. Power may be transmitted to the said rotating brushes 23, 24, 27 and 28 by pinions 30, 31, 32 and 33, arranged on the respective shafts of said brushes and driven by the said large gear 9. Likewise the supply-rollers, 22 and 26, are rotated by large pinions 34 and 35, respectively, mounted on the shafts thereof at the opposite side of the machine from the pinions and large gear just mentioned, and meshing with small pinions 36 and 37, respectively, on the shafts of the next adjacent brushes. It is obvious that the said rollers 22 and 26 will therefore rotate slower than the said applying-brushes, which further insures a sufficient amount of dressing being supplied to the brushes.

The gears and pinions herein described are of the long-toothed type, and the shafts of the rotary brushes and rollers as well as the shaft 4 of the cylinder, are journaled in sliding boxes or bearings, so that all said parts can be adjusted toward one another as the brushes wear or to secure increased pressure when desired. The adjustments of my improved machine are so numerous and so effective that its work may be adapted to any kind of leather.

The sig or black may be strained to remove any dirt therefrom before it is applied to the leather, and to this end I have provided certain strainers 38 and 39, in the supply pans 21 and 25, respectively.

The cylinder 8 rotates with comparative slowness, while the rotary brushes move at a comparatively high speed to insure a positive and substantial application of the different liquors employed. In operation the leather travels with the cylinder and conforms in shape to the periphery of the same at the top thereof, but the two sets of brushes are arranged on opposite sides of said top, one adjacent to each of the boards 15 and 16 and at that point of the cylinder to which said board is tangent. This enables the bending of the leather to take place between the two sets of brushes, and said brushes to operate on portions of the leather which are practically flat. Furthermore, as the second or finishing coat is also applied before the pores are closed, either by straightening the leather or by drying and hardening of the sig, a more perfect and permanent finish is secured.

Having thus described my invention, what I claim as new is:

1. In a leather blacking machine, the combination of a cylinder, brushes arranged along the outer surface of said cylinder forming therewith a passage-way for the leather, a large gear mounted in axial alinement with

said cylinder, pinions upon said brushes meshing with said gear, and means for independently driving said cylinder and large gear.

2. The combination of the cylinder, brushes arranged parallel to said cylinder adjacent to its outer surface and forming therewith a passage-way, a large gear in axial alinement with said cylinder, pinions upon the brushes meshing with said gear, supply rollers each adjacent to one of said brushes and driven therefrom, and means for independently driving said cylinder and large gear.

3. The combination with the cylinder and means for rotating the same, of brushes forming with said cylinder a passage-way, pinions on said brushes, a common driving gear for all said pinions, supply rollers each adjacent to one of said brushes, and means for driving said rollers from said brushes at their ends opposite those having the said pinions.

4. In a leather blacking machine, the combination with a cylinder and means for rotating the same, of rotary brushes arranged adjacent to said cylinder and forming therewith a passage-way for the leather, a common driving member adapted to rotate said brushes at a higher speed than that at which the surface of the cylinder moves, supply rollers each adjacent to one of said brushes, means for driving each supply roller from its adjacent brush at a slower rate of speed, means for adjusting said brushes with respect to the cylinder, and means for adjusting said rollers with respect to the brushes.

5. In a leather blacking machine, the combination of a cylinder, tangential feed and discharge boards inclined downwardly away from opposite sides of the cylinder at points near its top and including between them selves a portion of the cylinder surface forming a platen for the leather to travel over, a plurality of sets of brushes arranged in series adjacent to the outer surface of said platen and adapted to apply different coating successively to the leather, said sets being on opposite sides of the top of the cylinder and closely contiguous one to each of the said tangential boards, and means for rotating said cylinder and brushes.

6. In a leather blacking machine, the combination of a cylinder, tangential feed and discharge boards inclined downwardly away from opposite sides of the cylinder at points near its top and including between them selves a portion of the cylinder surface forming a platen for the leather to travel over, a plurality of sets of brushes arranged in series adjacent to the outer surface of said platen and adapted to apply different coating successively to the leather said sets being on opposite sides of the top of the cylinder and closely contiguous one to each of the said tangential boards, a large gear mounted in axial alinement with the cylinder, pinions on

the brushes meshing with said gear, means for independently drawing said cylinder and large gear, and means for adjusting said cylinder and brushes toward and away from each other.

7. The combination of the cylinder, a plurality of sets of rotary brushes arranged in series adjacent to the outer surface of said cylinder forming therewith a passage-way 10 and adapted to apply different coatings suc-

cessively to the leather, means for rotating said cylinder and brushes, and means for adjusting either said cylinder or said brushes with respect to the other and independent thereof.

LOUIS WIMMER.
